UNITED STATES PATENT OFFICE.

FRANK U. HAYMOND, OF ASHEVILLE, NORTH CAROLINA, ASSIGNOR OF ONE-HALF TO SAMUEL I. BEAN, OF ASHEVILLE, NORTH CAROLINA.

METALLIC RAILWAY-TIE.

SPECIFICATION forming part of Letters Patent No. 730,535, dated June 9, 1903.

Application filed December 17, 1902. Serial No. 135,573. (No model.)

To all whom it may concern:

Be it known that I, FRANK U. HAYMOND, a citizen of the United States, residing at Asheville, in the county of Buncombe, State of North Carolina, have invented certain new and useful Improvements in Metallic Railway-Ties, of which the following is a specification, reference being had therein to the accompanying drawings.

10 This invention relates to a metallic railway-tie, and particularly to means for supporting the rail thereon to prevent vibration and deaden the noise incident to the use of ordinary ties.

15 The invention has for its object to provide an improved construction of tie adapted to be provided with an elastic support secured therein upon which the rail is carried and with means for permitting a vibration of the 20 rail and limiting the extent thereof.

Other and further objects and advantages of the invention will be hereinafter set forth, and the novel features thereof defined by the appended claims.

25 In the drawings, Figure 1 is a longitudinal vertical section through one end of a tie constructed in accordance with this invention; Fig. 2, a top plan thereof; Fig. 3, a side elevation, and Fig. 4 a vertical cross-section of 30 a modified form of elastic support.

Like letters of reference refer to like parts in the several figures of the drawings.

The letter A designates the tie, which is preferably formed of sheet metal of one piece 35 of material bent into a rectangular form, having its ends connected at one side by an overlapping joint A', through which suitable rivets A² may be passed. In order to hold this tie against movement in the road-bed when 40 tamped, I have provided corrugated faces A³ upon the surfaces thereof and an angle-iron A⁴ upon the under face of the tie, which tend to prevent any longitudinal movement of the tie upon the road-bed. At each end of the tie

45 a suitable bracing-strip A⁵ may be secured to the upper and lower faces of the tie by means of the inwardly-extending ends A⁶ thereof. Upon the upper face of the tie at the proper distance apart for the gage of the rails guard- 50 lugs A⁷ are provided, and between these the

ordinary rail B is disposed, so that the base B' thereof fits snugly between the lugs A⁷ to prevent movement laterally of the rail. For the purpose of supporting the rail to permit a vertical vibration thereof an elastic body 55 may be used of any desired character—for instance, a coiled spring, as shown at C, which is provided at its upper end with a block C', passing through an aperture A⁸ in the top of the tie and resting on the under face of the 60 base of the rail to support the same at a slight distance above the face of the tie. At the lower end of the spring a base-plate C² is provided and secured to the under face of the tie by means of a bolt C³ passing through the 65 holder C⁴, around which the lower end of the spring is adapted to fit and be supported in position. For the purpose of limiting the vertical movement of the spring and rail suitable bolts C⁵ are passed through the base of 70 the rail and threaded into the upper surface of the tie, the heads of these bolts determining the extent of vertical movement of the rail. By an adjustment of these bolts the desired extent of movement may be secured. 75

When the tie is used upon a curve or other surface where an outward strain is exerted by the wheels of the car, a brace D may be provided and is secured at its outer end with bolts D' to the upper surface of the tie, while 80 its inner end is provided with a head D², normally lying slightly out of contact with the tread and web of the rail, but connected thereto by a bolt D³ extending through the web of the rail and threaded into a socket 85 D⁴, carried by the head D². The aperture through which the bolt D³ passes is slightly larger than the diameter of the bolt, and the connection of these parts thus provides for the necessary vibration of the rail without 90 danger of breaking the bolt and yet supplies a firm brace against an outward movement of the rail when pressure is exerted in that direction.

In Fig. 4 a modified form of elastic body is 95 shown and may comprise a solid body E, of rubber, leather, or other suitable material, held at its lower portion by a socket E', carried by a base-plate E² upon the under face 100 of the tie, while the upper end of the elastic

body is surrounded by a similar socket E³, carrying the contact-plate E⁴, pressing against the under side of the base B' of the rail.

It will be obvious that changes may be made 5 in the details of construction and configuration without departing from the spirit of the invention as defined by the appended claims.

Having described my invention and set forth its merits, what I claim, and desire to 10 secure by Letters Patent, is—

1. In a metallic railway-tie, a plate bent and secured together at its free ends to form an open-ended shell having a closed upper surface with an aperture therein, guard-lugs 15 upon said upper surface spaced from the opposite sides of the aperture therein, and an elastic supporting-body disposed within the case beneath said aperture to contact with the base of a rail between the side edges there- 20 of, substantially as specified.

2. In a metallic railway-tie, a metallic shell having an aperture in its upper face, an elastic body supported beneath said aperture and within the shell, a rail adapted to rest upon 25 the upper end of said elastic body, guard-lugs at the opposite sides of the base of said rail, a brace carried by the upper face of said shell at one side of said rail, and a bolt extending through an enlarged aperture in the rail and 30 secured to said brace for permitting a vertical movement of the rail; substantially as specified.

3. In a metallic railway-tie, a metallic shell having an aperture in its upper face, an elastic body supported beneath said aperture and within the shell, a rail adapted to rest upon 35 the upper end of said elastic body, guard-lugs at the opposite sides of the base of said rail,

a brace carried by the upper face of said shell at one side of said rail, a connection between 40 said brace and rail for permitting a vertical movement of the latter, and bolts passed through the base of said rail and secured to said tie to limit the vertical movement of the rail; substantially as specified. 45

4. A metallic railway-tie comprising a continuous plate jointed at one side thereof and corrugated upon its sides and under face, and a brace extending from the under to the upper face of said tie; substantially as specified. 50

5. In a metallic railway-tie, a rail adapted to rest thereon, an elastic support for said rail, a brace secured at one end to said tie and provided at its opposite end with a head having a threaded socket, and a connecting-bolt extending through an enlarged aperture in the web of the rail and entering said socket; 55 substantially as specified.

6. In a metallic railway-tie, a rail adapted to rest thereon, an elastic support for said 60 rail, a brace secured at one end to said tie and provided at its opposite end with a head having a threaded socket, a connecting-bolt extending through an enlarged aperture in the web of the rail and entering said socket, 65 guard-lugs at opposite sides of the base of said rail to prevent lateral movement thereof, and adjustable bolts passed through the base of said rail and secured to the upper face of said tie; substantially as specified. 70

In testimony whereof I affix my signature in presence of two witnesses.

FRANK U. HAYMOND.
